HEAT EXCHANGER

Samuel Cornette Collins, Watertown, Mass., assignor to Joy Manufacturing Company, Pittsburgh, Pa., a corporation of Pennsylvania

Application January 17, 1948, Serial No. 2,877

3 Claims. (Cl. 257—245)

1

My invention relates to heat exchangers, and more particularly, but not exclusively, to heat exchangers of a type which is well adapted for use in apparatus for the separation of gases, for example the separation of air into its principal constituents.

In apparatus for separating air into its constituents, it is necessary to reduce the temperature of the entering air and to remove from it carbon dioxide and water vapor, and it is important to save as much of the refrigeration as possible. These ends may be accomplished by using reversing heat exchangers. In such a heat exchanger, at a given moment, air will enter the system through one course while the nitrogen product leaves through another, the fluids moving in counterflow relation. Periodically the inflow of air will be switched to the course through which nitrogen has been leaving, and the outflow of nitrogen will be switched to the course through which air has been entering. Carbon dioxide and water vapor in the entering air will be frozen out and deposited in the heat exchanger courses while these are being traversed by the entering air. The nitrogen, on its way out, sublimes the carbon dioxide snow and ice, and carries these impurities out of the system. In some heat exchangers, to increase the cooling of the entering air, a third course may be provided, and the oxygen product is passed through this third course on its way to storage or use. Its flow is not shifted periodically and is, desirably, at all times, in counterflow relation to the entering air. Such heat exchangers—whether of the two-course or three-course type—may assume various forms, and it is a purpose of my invention to provide an improved heat exchanger of each type.

Among the numerous varieties of heat exchangers are those in which the moving streams of substances between which heat exchange is to be effected have heat transmission effected largely by conduction through substantial distances by the metal forming the walls of the passages, rather than by a direct transmission from one side to the other of metal walls which lie between and separate the flowing streams of substances between which heat transfer is to be effected. For example, two substances at different temperatures may be admitted to adjacent passages and kept separated from each other by walls of substantial thickness but of relatively small dimension in a direction at right angles to the flow, while the passages have much greater width and the streams have much more extensive contact.

5 with walls of the passages which are at right angles to the walls first mentioned; and most of the heat transfer is effected by the giving up of heat to these second walls by the warmer substance, its transfer through the metal of these walls from one side to the other of the separating walls, and the picking up of heat by the other substance from other wall areas of relatively large extent at the opposite side of the separating wall.

10 This type of heat exchange device is not broadly new, and for efficiency of operation and to permit the transfer of considerable quantities of heat between two fluids in a reasonably short period of time, and with small differences in temperature, I have found that substantial changes from prior constructions are necessary. With such heat exchangers, which may be made up of series of separators welded, brazed or soldered to metal plates in such a manner that a number of thin fluid streams may pass in the same direction, it is necessary to space the supply and discharge connections for each fluid as far apart as is practicable, in order to avoid the leakage of heat through the plates from one end to the other. It is also possible, I have found, by transversely slotting the passage walls not only to reduce, to a very marked degree, the heat transfer longitudinally through the metal of the walls, but also to set up within the passages series of successive turbulences so that the fluid, which absorbs heat mainly in its layers in direct contact with the plates, through oft-repeated changes in velocity undergoes repeated mixing of its constituent portions, and between each imperforate passage wall portion and the next there is at least a partial remixing of the fluid, so that the heating of certain portions thereof (or conversely the cooling), while other portions remain with little change in temperature, is avoided.

15 It is an object of my invention to provide an improved heat exchanger. It is another object of my invention to provide an improved heat exchanger formed of thin plate sections and separating elements. It is a further object of my invention to provide an improved heat exchanger of an improved construction for the transfer of heat between entering streams of air and leaving streams of nitrogen flowing relative to an apparatus for separating air into its constituents. It is still another object of my invention to provide an improved heat exchanger having not only courses for the flow—preferably in counterflow relationship—of streams of air under pressure and nitrogen, but also having, in a modified arrangement, 20 a third passage so that a leaving stream of oxygen

may flow in heat exchange relation to the other streams. It is still another object of my invention to provide an improved form of heat exchanger in which heat loss will be minimized and in which the maximum possible amount of heat will be transferred through the walls of the heat exchanger from one substance to another, with a minimum loss of heat through the material of the heat exchanger from the hot end to the cold end of the latter. Still a further object of my invention is to provide an improved heat exchanger having an improved means for effecting repeated turbulences in the flowing streams, with the result that there shall not be a mere stratified heating and cooling of the substances in heat exchange relationship. Still another object of my invention is to provide an improved heat exchanger structure. The chief criterion of a superior heat exchanger is its efficiency, which is based upon the quantity of heat transferred per degree difference in temperature between the two counterstreams. Yet a further object of my invention is to provide an improved construction of heat exchanger for the interchange of heat between three substances. It is still another object of my invention to provide an improved heat exchanger which shall transfer a maximum possible quantity of heat per degree of difference in temperature between the counterstreams of fluid, which shall insure the maximum efficiency of heat transfer between its walls and the fluids flowing in contact with said walls by insuring maximum possible temperature differences between the streams and walls at all points by causing the warmer portions of such streams repeatedly to be remixed with the cooler portions, or vice versa, so that the flowing streams will have their portions in contact with the heat transfer walls continually rebrought to a condition of maximum possible temperature difference with respect to said walls; and in which heat leakage by conduction through the walls of the exchanger between the hot and cold ends thereof shall be kept at a minimum with a resultant improved utilization of the temperature difference available to effect heat transfer. Other objects and advantages of the invention will hereinafter more fully appear.

In the accompanying drawings, in which one form and several modifications which my invention may assume in practice have been shown for purposes of illustration,

Fig. 1 is an elevational view of a vertically disposed heat exchanger and with parts broken away, showing an illustrative embodiment of the invention in which provision is made for heat exchange between two substances.

Fig. 2 is another elevational view of the structure which is shown in Fig. 1, turned through 90° and with parts broken away to show details of interior construction.

Fig. 3 is a view of one end of the exchanger shown in Figs. 1 and 2, with parts broken out, and particularly showing manifold arrangements.

Fig. 4 is a horizontal transverse section on the plane of the line 4—4 of Fig. 1 on a larger scale, while

Fig. 5 is a similar horizontal transverse sectional view on the plane of the line 5—5 of Fig. 1.

Fig. 6 is a fragmentary sectional view on the plane of the line 6—6 of Fig. 4.

Fig. 7 is an enlarged fragmentary sectional view on the plane of the line 7—7 of Fig. 1.

Fig. 8 is an enlarged horizontal sectional view, on a plane parallel to the plane of the section

line 7—7, showing a modified form of construction, the modification inhering particularly in the manner of forming partitions between the flow passages.

Fig. 9 is a view generally similar to Fig. 3, showing one arrangement for the inclusion of a third fluid in the heat exchanger.

Fig. 10 is an enlarged fragmentary section showing a detail of construction of the modification of Fig. 9.

Fig. 11 is a view of another modification in which there are different arrangements for heat transfer with respect to a third fluid.

Fig. 12 is an enlarged fragmentary sectional view of the construction shown in Fig. 11, the section being taken approximately on the plane of the line 12—12 of Fig. 13.

Fig. 13 is a sectional view on the plane of the line 13—13 of Fig. 11.

Fig. 14 is a detail showing another modified form of construction.

Fig. 15 is an enlarged fragmentary view looking at the face of one of the perforated sheets, showing still another modified form of construction.

Fig. 16 is a sectional view taken on the plane of the line 16—16 of Fig. 15.

Referring to the drawings, and first to Figs. 1 to 7 thereof, it will be observed that I have shown a large number of relatively long, narrow, perforated sheets 20, each provided at 21 with series of parallel transverse openings. These sheets may desirably be of copper or other material which is a good conductor of heat. In one physical embodiment of the invention, which will of course be understood to be described merely for purposes of illustration, and not to imply any limitation, the perforated sheets will be on the order of six feet long, six inches wide, from ten to twenty thousandths of an inch thick—.0125" is a desirable value. For the other dimensions enumerated, I have rows of six aligned perforations or slots 21 each perhaps one-sixteenth of an inch wide and some three-eighths and others one inch long, and spaced from one another lengthwise of the sheets by distances on the order of their widths or a small multiple thereof; and the sheets may be arranged about .020" apart. The function of the slots is to reduce heat conduction longitudinally of the sheets and to increase the heat transfer coefficient as later described. Figs. 1 to 7 show the slots 21 in six rows, from points near one end of the sheets to points near the other end; and the rows are separated by relatively narrow imperforate portions of the sheets, and there are relatively narrow imperforate edge portions at each side edge of each sheet. The several rows of slots are indicated for easy reference as 22, 23, 24, 25, 26 and 27. Between the first slot in each row and the extreme opposite slot, the rows of slots are continuous except at points where clamping bolts are to be provided, such clamping bolts, 28, passing as shown in Fig. 7 through openings 29 just enough larger than the bolts to provide comfortable clearance.

Each of the plates 20, in addition to the numerous relatively long narrow parallel slots through it, is traversed by openings or windows through which fluid may flow from appropriate headers, shortly to be described, into the spaces between the plates. These openings are designated by the same reference characters as the slots with which they are respectively associated, the openings at one end of each row being designated by the suffix A and those at the other end of each row by the suffix B. There are thus in

each plate, openings or windows 22A, 23A, 24A, 25A, 26A and 27A at one end of the strip, and openings 22B, 23B, 24B, 25B, 26B and 27B at the other end of the strip, in the construction illustrated.

Between each pair of plates there extend a series of longitudinally arranged wires or other partition elements, these being of such a dimension perpendicular to the planes of the plates as is requisite to provide the desired thickness of stream between each pair of plates. These wires include side sealing wires 30 and 31, and five other wires 32, 33, 34, 35 and 36; and the series of slots 22, the openings or windows 22A and 22B, and the openings 29 which lie between the ends of the row of slots 22 all lie between the wires or partitions 30 and 32. In like manner, it will be understood that the slots 23 and the openings 23A and 23B and other openings 29 lie between the wires or partitions 32 and 33. It is unnecessary to enumerate the relation of the other series of openings and slots to the other pairs of wires or partitions in detail, it being enough to say that between wires or partitions 33 and 34 the slots 24 and associated openings are disposed, between the wires or partitions 34 and 35 the slots 25 and associated openings are disposed, between the wires or partitions 35 and 36 the slots 26 and associated openings are disposed, and the slots 27 and associated openings are disposed between the wires or partitions 36 and 31.

The wires may, as shown in Fig. 7, not all be arranged with their axes in a common plane, but may be slightly staggered laterally relative to each other so as to provide a certain degree of flexibility. The wires may be soldered in place, or brazed in place, in any suitable manner, and if desired the entire "pack" of plates and wires may be dipped when desirable in a suitable bath of molten metal, such as solder, to effect the sealing of the walls of the many passages. The opposite ends of the spaces between each pair of longitudinally extending wires or partitions is closed as by short elements E soldered or brazed in position, so as to seal the end of each passage formed between the various plates. Next to and outside of the most widely separated plates 20, there are relatively heavy, rigid, outside plates 37 and 38. Each of these plates is shown as having openings or windows in it, later referred to by reference characters, overlying the openings 22A to 27A and 22B to 27B. They might, however, be windowed only in the same way their associated headers are windowed, if desired.

To conduct fluid to the passages formed by the plates, various header arrangements may be employed. For example, end headers similar to those shown in my application Serial No. 3217 filed January 20, 1948, might be employed by omitting end seals and fixing headers to the ends of the plate stack. For purposes of illustration in this case, however, I have shown header elements bolted to the opposite ends of the outside plate 37 and other header elements bolted to the outside plate 38. These may be considered as being in top and bottom pairs, the top pairs numbered 39 and 40 and the bottom pairs numbered 41 and 42. The top header 39 has, as shown, an end connection 44, say for the admission of one of the substances whose heat content is to be changed, and it contains a chamber 45 and has a plane wall 46 in which there are formed a relatively narrow opening 47 and two wider openings 48 and 49. These three openings communicate with the openings 22A, 24A and 26A in the series

of perforated plates 20, having such communication through corresponding openings 47', 48' and 49' formed in the outside plate 37. It will thus be evident that the fluid entering the chamber 45 may pass through the openings 22A, 24A and 26A in the perforated plates 20 and the openings in the outside plate 38, all the way to the wall of the header 40 which is imperforate in line with the series of slots 47', 48' and 49'. Thus fluid can enter all of the longitudinal passages bounded laterally by the wires or partition elements 30, 32; 33, 34; and 35, 36. The top header 40 has, if 39 is a supply header, a connection 51 for the egress of one of the substances which undergoes heat exchange, and contains a chamber 52 having openings 53, 54 and 55, connected by openings 53', 54' and 55' formed in the outside plate 38, with the openings 23A, 25A and 27A in the adjacent one of the plates 20 and with all the other openings bearing corresponding numbers all the way to the wall 46, which is imperforate in line with the openings 53', 54' and 55'.

At the other end of the heat exchanger, as shown in Fig. 5, the header 41 is provided with an ingress (ingress, if 40 is a discharge header) connection 59, and a chamber 60, which, through openings 61, 62 and 63, and corresponding openings 61', 62' and 63' in the outside plate 37 communicates with the openings 23B, 25B and 27B in the adjacent perforated plate 20 and in all of the other plates 20. The wall of the header 42 is imperforate in line with the series of openings 23B, 25B and 27B.

The header 42 has (assuming the header 39 to be a supply header) a delivery connection 65, and a chamber 66 which communicates through openings 67, 68 and 69, and corresponding openings 67', 68' and 69' in the outside plate 38, with the slots 22B, 24B and 26B in the adjacent perforated plate 20, and with the corresponding slots in all of the other plates lying between the outside plates. The wall of the header 41 is imperforate in its portions which are in line with the series of openings 22B, 24B and 26B. Thus it will be apparent that one fluid entering through the connection 44 will have access to all of the openings 22A, 24A and 26A, and at the other end of the heat exchanger the openings 22B, 24B and 26B communicate with the header 42, so that there will be flow in three series of parallel passages from the top header 39 to the bottom header 42; and, correspondingly, there will be counterflow from the bottom header 41 to the top header 40 at the other end of the exchanger.

When the heat exchanger is to be used as a reversing heat exchanger, the headers 39 and 40 will alternatively serve as means for the admission of one fluid, while the headers 41 and 42 will serve alternatively as means for the admission of the other fluid, and there will be alternatively flow of one fluid in at 39 and out at 42 and of the other in at 41 and out at 40, and flow of the first fluid in at 40 and out at 41 and of the other in at 42 and out at 39.

By reason of the slots 22, 23, etc., which greatly reduce the freedom of heat transfer lengthwise of the plates 20, there will be very little heat loss lengthwise of these plates through the metal of the heat exchanger, but the heat absorbed by the portions of these plates surrounding one series of openings will be conducted very effectively through the metal of the plates to the metal surrounding the adjacent series of perforations, or pair of series, as the case may be. As the fluids flow longitudinally between the

plates, each time they pass between imperforate wall portions, there is a heat transfer between the opposite sides of the fluid streams and the wall portions. Each time the fluid passes out from between a pair of opposed wall portions to a space between slots, there will be an expansion, and a marked turbulence, and a re-mixing of the fluids which had had their outermost layers, so to speak, undergo a slight change in temperature.

In Fig. 8, a modification of the arrangements for forming the lateral walls of the fluid conducting passages is shown. In this view, instead of using the round wire-like partition elements 30, 31, etc., material rectangular in cross section is indicated at 71, and when the heat exchanger is assembled, wire solder 72 is placed alongside each partition member and suitably held there so that when the bank of exchanger plates and partition members have been fully assembled, they may be heated and the solder melted and caused to flow by capillary action through the joints between plate and partition elements and effect sealing.

In the use of the apparatus so far described in an air separation plant, it will be understood that there will be provided appropriate valve mechanisms which will permit switching of the nitrogen and air between the sets of passages, but that the nitrogen will always flow longitudinally of the heat exchanger in one direction while the air will always flow in the other direction, irrespective of which passage series conducts either fluid. Ordinarily, the air will enter at the bottom and the nitrogen at the top of the courses through which they flow.

As previously indicated, in the provision of a heat exchanger for use in the separation of air into its principal constituents, it may be desirable to have the oxygen product, as well as the nitrogen product, pass through the heat exchanger. It is desirable that the passages for the entering air and leaving nitrogen shall be of relatively equal cumulative cross sectional areas. The oxygen conduits, however, need not be so large, and particularly if oxygen under substantial pressure is to be the product the cross sectional area of the oxygen conducting passages may be made relatively small in comparison with the passages for the flow of nitrogen and of entering air.

In Figs. 9 and 10, and in Figs. 11, 12 and 13, two different modifications of the invention are illustrated, these showing three-pass heat exchangers, and the oxygen is, in each case, conducted in counterflow relation to the entering air. Thus, if it be assumed that at one time the nitrogen enters through the header 39 and leaves by way of the header 42, and that at other times the nitrogen enters by way of the header 40 and leaves by way of the header 41, it would be desirable to have the oxygen enter through header means at the same end of the exchanger as headers 39 and 40, at the same end as the nitrogen, and leave at the same end as the headers 41 and 42, i. e. at the same end as the nitrogen. In the construction shown in Figs. 9 and 10, there are provided pairs of horizontal headers 81, 81 and 82, 82 at the opposite ends of the plate bank, the pair of headers 81 at the same end as the headers 39 and 40, and the headers 82 at the same end of the heat exchanger as the headers 41 and 42. These headers have suitably secured to them and in communication with their interiors, which may be

regarded for purposes of illustration as cylindrical, parallel series of vertical tubes 83, these tubes being of suitable cross section to provide for the necessary flow volume, and being brazed, soldered, or otherwise suitably secured to the side edges of the plate banks, as shown in Fig. 10 to provide for efficient heat transfer. Oxygen product may be delivered to the headers 81 by a conduit 85, a T 86, and branch connections 87 leading to the headers 81, and, having passed through the longitudinally extending tubes 83, will enter the hollow headers 82 and be delivered from the latter to discharge conduits 88, which may obviously be connected together, if desired. Thus it will be apparent that the oxygen conducting pass of the heat exchanger in the form of a series of tubes, in good heat exchange relation to the plate banks, and headers with which the tubes communicate, may be arranged on the outside of the plate bank heat exchanger first described. It is also possible, however, to form the plates 20 in two lateral halves, as at 20', each half having, for example, four rows of slots in it and four windows at either end, two sets of windows and two rows of slots in each half being used in association with fluid flow in either direction. Then, by the provision of a header such as 90 at one end, and a parallel header at the other end, this other header not being shown, and a bank of longitudinally extending tubes each side by side as at 91 arranged between and soldered or brazed to the edges of the two banks of plates, as shown in Figs. 11, 12 and 13, there may be effected the conducting of oxygen in heat exchange relation to the plate-and-separator-constituted fluid conducting means.

In Fig. 14, there is shown an arrangement of the slotted plates 20'' in which, instead of having separate wire or partition elements, there are longitudinally extending beads 95 formed on each plate, and when the plates are assembled, wire solder, as at 96, is laid in each bead so that upon the heating of the assembled unit the solder may effect a seal along the outer surface of one bead and the contacting inner surface of the next adjacent bead. Thereby, a readily and effectively sealed arrangement will be produced and the structure will not have to have a lot of separator wires or partition elements carefully laid with respect to each pair of plates.

It is desirable that there shall not have to be too large a pressure differential between the opposite ends of the heat exchangers. Turbulence creation may be accomplished primarily by mere velocity changes, or in part also by partial baffling of the flowing streams of fluids. When the edges of the slots 21 are relatively sharp, there is some baffling action, with excellent turbulence creation but also some increase in flow resistance. In Figs. 15 and 16, the plates 20''' are twice rolled—though they could be otherwise formed—being perforated in one set of rolls and being then fed through another set to form the metal M between the slots more or less oval in cross section, so as to cause the turbulence to be produced more by the change in velocity, as it were, and to diminish corner or edge action of the imperforate portions—the bars so to speak—on the layers or streams of fluid.

From the foregoing description, it will be apparent that I have provided an improved heat exchanger; that I have provided an improved heat exchanger of the two course and also of the three course type; and that the heat ex-

changer will be of great efficiency in that there will be, due to the fact that the length of the slotted plate sections is relatively great, little heat loss by direct conduction longitudinally of the plates, such conduction being largely prevented by the employment of the slots. It will further be observed that because of the many turbulences produced as the fluid passes from between imperforate plate sections to perforated plate sections, with the resultant internal remixing, as it were, of the constituents of the moving ribbon-like streams of air or gas, the maximum rate of heat transfer from plates to fluid will take place, because the mean difference between the fluid temperature and the plate temperature will always be maintained at a substantial maximum. The structure is comparatively easily built, is strong, is not likely to be damaged even by the use of considerable pressures, may readily be sealed in a manner to prevent leakage, and, through the multiplicity of channels provided, can handle relatively large quantities of fluid although not of great overall transverse dimension.

It will of course be understood that the dimensions given are but illustrative and that while a construction, of a length of several feet and slotted and of the illustrative thicknesses of material described will be very effective for a heat exchanger of a given capacity, very wide variations in thickness, size and number of plates, slot width and breadth, number of rows of slots, etc. are within the purview of my invention.

While there are in this application specifically described two forms and modifications of each which my invention may assume in practice, it will be understood that these forms and modifications are shown for purposes of illustration and that the invention may be further modified and embodied in various other forms without departing from its spirit or the scope of the appended claims.

What I claim as new and desire to secure by Letters Patent is:

1. In a heat exchanger, in combination, sets of thin elongated plates stacked side-by-side each having throughout the greater portion of its length a plurality of rows of relatively long narrow slots, means cooperating with said plates to space the same and to coat with the same to form longitudinally extending passages transverse of the slots and substantially parallel with said rows, the slots providing communication transverse of the plates and from one part of a passage to another part of a passage, a first header adjacent one end of the stacked plates and having a wall with spaced openings communicating with alternate passages, a second header adjacent the same end of the stack and having a wall with spaced openings communicating with passages intermediate the alternate passages, a third header adjacent the opposite end of the stacked plates and having a wall with spaced openings communicating with said intermediate passages, a fourth header at the same end as the third-named header and having a wall with spaced openings communicating with the alternate passages, whereby a fluid may flow through the first-named header and the fourth-named header and pass through the alternate passages, and still another fluid may flow through the second-named header and the third-named header and pass through the intermediate passages, and tubular flow conduits extending longitudinally between pairs of said sets of plates in-

termediate pairs of said coating means, certain of said sets of plates being secured to the adjacent sides of said tubular conduits, said tubular conduits providing passage for a third fluid.

2. In a heat exchanger, in combination, sets of thin elongated plates arranged side-by-side to form a stack and each having throughout the greater portion of its length a plurality of rows of relatively long narrow slots, and having openings between its own ends and the ends of said rows, means cooperating with said plates to space the same and to coat with the same to form longitudinally extending passages transverse of the slots and substantially parallel with said rows, the slots providing communication transverse of the plates and from one part of a passage to another part of a passage, a first header adjacent one end of the stacked plates on one side of the stack and having a wall with spaced openings aligned with alternate openings in said plates and thus communicating with alternate passages, a second header adjacent the same end of the stack and having a wall with spaced openings communicating with openings in the plates intermediate the alternate openings and thus communicating with passages intermediate the alternate passages, a third header adjacent the opposite end of the stacked plates and having a wall with spaced openings aligned with openings in the plates to communicate the spaced openings of the header with said intermediate passages, a fourth header at the same end as the third-named header and having a wall with spaced openings aligned with openings in the plates to communicate the fourth-named header with the alternate passages, whereby a fluid may flow through the first-named header and the fourth-named header and pass through the alternate passages, and still another fluid may flow through the second-named header and the third-named header and pass through the intermediate passages, and tubular flow conduits extending longitudinally between pairs of said sets of plates intermediate pairs of said coating means, certain of said sets of plates being secured to the adjacent sides of said tubular conduits, said tubular conduits providing passage for a third fluid.

3. In a heat exchanger, a plurality of relatively thin plates arranged side-by-side and heavier outside plates, and partition elements cooperating with said plates to form a plurality of long, relatively wide and relatively shallow passages separated from each other at their edges by said partition elements, each of said relatively thin plates having a series of long narrow slots formed through it and arranged in rows, the length of said slots being nearly equal to the width of said passages, all of said plates having larger openings near both ends for conducting fluid with respect to said passages and each of said thin plates having one such opening at each end of each row of slots, a first header adjacent one end of the stacked plates on one side of the stack and having a wall with spaced openings communicating with alternate passages through alternate ones of said larger openings, a second header adjacent the same end of the stack and having a wall with spaced openings communicating with passages intermediate the alternate passages through larger openings intermediate said alternate larger openings, a third header adjacent the opposite end of the stacked plates and having a wall with spaced openings communicating with

said intermediate passages through other alternate ones of said larger openings, and a fourth header at the same end as the third-named header and having a wall with spaced openings communicating with the alternate passages through larger openings intermediate said other alternate larger openings, whereby a fluid may flow through the first-named header and the fourth-named header and pass through the alternate passages, and still another fluid may flow 10 through the second-named header and the third-named header and pass through the intermediate passages.

SAMUEL CORNETTE COLLINS.
